Primary Examiner — Kimberly Barnes(74) *Attorney, Agent, or Firm* — Saidman DesignLaw Group, LLC(57) **CLAIM**

The ornamental design for a panel, as shown and described.

DESCRIPTION

FIG. 1 is a front view of a panel showing my new design in an environment of use;

FIG. 2 is a right side view thereof;

FIG. 3 is a left side view thereof;

FIG. 4 is another front view thereof;

FIG. 5 is a rear view thereof;

FIG. 6 is a top view thereof; and,

FIG. 7 is a bottom view thereof.

The broken lines in FIG. 1 illustrate environmental subject matter which forms no part of the claimed design. The broken lines in FIGS. 2, 5 and 7 illustrate portions of the panel which form no part of the claimed design.
